(57) **CLAIM**

The ornamental design for a light reflector, as shown and described.

DESCRIPTION

FIG. 1 is a front, right, top perspective view of a light reflector showing our new design;

FIG. 2 is a front, left, top perspective view thereof;

FIG. 3 is a front, right, bottom perspective view thereof;

FIG. 4 is a front, left, bottom perspective view thereof;

FIG. 5 is a back, right, top perspective view thereof;

FIG. 6 is a back, left, top perspective view thereof;

FIG. 7 is a back, right, bottom perspective view thereof;

FIG. 8 is a back, left, bottom perspective view thereof;

FIG. 9 is a front side view thereof;

FIG. 10 is a back side view thereof;

FIG. 11 is a right side view thereof;

FIG. 12 is a left side view thereof;

FIG. 13 is a top view thereof;

FIG. 14 is a bottom view thereof;

FIG. 15 is an additional front side view thereof, shown in a different orientation;

FIG. 16 is a front side view of a second embodiment thereof, the only difference being the number of reflectors;

FIG. 17 is front side view of a third embodiment thereof, the only difference being the number of reflectors; and,

FIG. 18 is a front side view of a fourth embodiment thereof, the only difference being the number of reflectors.
